UNITED STATES PATENT OFFICE

ALEXANDER T. BODLE, OF MISHAWAKA, INDIANA, ASSIGNOR TO DODGE MANUFACTURING CORPORATION, OF WILMINGTON, DELAWARE, A CORPORATION OF DELAWARE

CONVEYER CHAIN

Application filed October 6, 1928. Serial No. 310,723.

This invention relates to conveyer chains. The object is to improve such chains more particularly with reference to the pivot connections.

5 The invention will be explained by reference to an illustrative embodiment thereof shown in the accompanying drawings, and will be pointed out in the claims.

In said drawings:

10 Fig. 1 is a plan view of a short length or section of a conveyer chain of one practicable construction, containing an embodiment of the invention.

Fig. 2 is a side elevation thereof.

15 Fig. 3 is a side view of one of the outside link bars.

Fig. 4 is a detail view on an enlarged scale of one of the locking pins for fastening the pivot pins.

20 Fig. 5 is a side view of one of the inside link bars.

Fig. 6 is an enlarged perspective view of one of the pivot bushings.

A sufficient length of the illustrative chain 25 is shown in the drawings to disclose the connections between several links. In the construction shown, the links comprise pairs of parallel link bars, alternate pairs arranged outside of and overlapping with the others.

30 The inside link bars are designated in the drawings by the numeral 10, and the overlapping outside link bars are designated by the numeral 11. The link bars at one side of the chain are shown provided with attaching 35 brackets 12 for attachment of cross bars (not shown) by which to connect the chain with another parallel chain. It will be understood that such cross bars are commonly used to support loads conveyed by the chains.

40 The chain links are connected by pivot pins 13 inserted through the outside link bars and through bushings 14 fitted in the inside link bars. Track rollers 15 are shown mounted on said bushings between the inside link bars.

45 The pivot pins 13 are shown as plain headed pins having transverse openings through their fore ends, and are retained and fastened in place by locking pins 16 inserted through said openings. These locking pins may con-

55 having bent head ends 17 and having their opposite ends preferably tapered as indicated at 18. The outside link bars at the side of the chain adjacent to the locking pins, one of which bars is more clearly shown in Fig. 3, are provided with end notches 19 and with keeper openings 20 for engagement with the ends 18 of the locking pins; said notches 19 and keeper openings 20 being at opposite sides of the pivot pin openings 21. When the locking pins are inserted through the pivot pins, 60 the bent ends or heads 17 of the locking pins engage in the notches 19, and the other ends of the locking pins are then bent into the keeper openings 20, as shown in Fig. 1, thus interlocking the locking pins with the outside link bars and thereby holding the pivot pins in non-rotatable relation to the outside links. The bushings 14, in which the pivot pins have 65 a rotatable fit, are themselves secured in non-rotatable relation to the inside link bars. For instance, the ends of the bushings may be exteriorly deformed, as indicated at 22 in Fig. 6, and fitted in similarly shaped bush 70 openings 23 in the inside link bars, such bush 75 openings being shown in Fig. 5.

Thus the pivot pins and bushings, while freely rotatable in relation to each other, are respectively held in rigid relationship to the respective link ends with which they are connected, so that the chain links can move relatively to each other only in accordance with the rotative movement of the pins in the bushings, or in other words the relative angular movements of the links, as when passing 80 around sprocket wheels, must be in unison with the movements of the pins and bushings respectively connected to the link ends. This is important to avoid wear of the link bars, 85 which are usually of comparatively soft metal as distinguished from the pivot pins and bushings which are of hardened steel. The locking of the pivot pins in non-rotatable connection with the outside links through the locking pins, permits the employment of plain 90 headed pivot pins, while the connection therewith to the outside links is exceedingly simple.

Obviously the invention is not restricted to the particular embodiment herein shown and described.

What I claim as my invention, and desire to secure by Letters Patent, is:

1. A conveyer chain comprising pivotally connected link bars and embodying pivot pins, locking pins for said pivot pins, and bushings in which the pivot pins are rotatably fitted, said bushings being non-rotatably mounted in ends of link bars connected by the pivot pins to ends of adjacent link bars, and said locking pins inserted through said pivot pins and fastened in such manner as to hold the pivot pins in non-rotatable relation to the last mentioned link bars, so that the links can move relative to one another only in unison with the pins and bushings.
- 15 2. A conveyer chain comprising pivotally connected link bars and embodying pivot pins, locking pins for said pivot pins, and bushings in which the pivot pins are rotatably fitted, said bushings being non-rotatably mounted in ends of link bars connected by the pivot pins to ends of adjacent link bars, and said locking pins being interlocked with the last mentioned link bars to hold the pivot pins in non-rotatable relation thereto, for the purpose described.
- 20 3. A conveyer chain comprising pivotally connected link bars, including link bars having end notches and keeper openings, and embodying pivot pins, locking pins for said pivot pins, and bushings in which the pivot pins are rotatably fitted, said bushings and pivot pins connected respectively with adjacent ends of adjacent link bars, and said locking pins consisting of pins having bent head ends engaging said notches and their opposite ends bent into and engaging said keeper openings.
- 25 4. A conveyer chain comprising alternating pairs of outside and inside link bars, said inside bars having bush openings and bushings non-rotatably mounted therein, said outside bars having pivot pin openings, headed pivot pins inserted through said outside bars and bushings, the outside bars at the side of the chain opposite the heads of the pivot pins having end notches and keeper openings, and locking pins inserted through the unheaded ends of the pivot pins, said locking pins consisting of pins having bent head ends engaging said notches and having their opposite ends bent into and engaging said keeper openings, whereby the pivot pins are held in non-rotatable relation to the outside bars.

In testimony whereof, I have signed my name to this specification.

ALEXANDER T. BODLE.
